UNITED STATES PATENT OFFICE.

ALLEN F. WILSON, OF CLAYTON, NEW JERSEY, ASSIGNOR OF ONE-HALF TO
JOHN W. WEBB, OF CLAYTON, NEW JERSEY.

MEANS FOR CLOSING AIR-TIGHT JARS.

SPECIFICATION forming part of Letters Patent No. 723,508, dated March 24, 1903.

Application filed November 19, 1902. Serial No. 131,978. (No model.)

To all whom it may concern:

Be it known that I, ALLEN F. WILSON, a citizen of the United States, residing at Clayton, in the county of Gloucester and State of New Jersey, have invented a new and useful Improvement in Closing Air-Tight Jars, of which the following is a specification.

This invention relates to the closing of air-tight jars, such as are used for preserving alimentary substances, and has for its object greater facility of closing and opening, greater certainty of air-tight closure, and better durability of the jars and covers and packing for repeated use; and to this end it consists in an improved construction of cover or cap and in combination therewith an improved form of neck for the jars, between which covers and necks I interpose an improved form of packing or gasket.

The construction of my invention is shown in the accompanying drawings, in which—

Figure 1 is a vertical section of a jar neck and cap embodying this invention. Fig. 2 is an inverted plan view of a cap. Fig. 3 is a plan view of the neck; Fig. 4, an elevation of the neck. Fig. 5 shows an enlarged section of a part of the gasket and adjacent parts before closing, and Fig. 6 shows a like section of the same parts when closed.

Referring to the drawings, 1 represents the neck of a jar, having a shoulder 2 where it joins the body as nearly flat as is consistent with the delivery of the jar from the mold. A short distance above the shoulder 2 is a circumferential bead 3, leaving a groove 12 between them, and above the bead a plurality of segmental projections 4. Above the projection 4 is a cylindric neck 5, terminating in a flat surface 6. The jars as described may be formed in a mold, and the surface 6 may be ground flat in the usual manner.

7 is the cap, of such diameter near the top as to fit easily on the neck 5 and below at the part below of such diameter as to fit closely around the segmental projections 4 and bead 3 and at the lower edge is rounded or beaded to a convex cross-section. A gasket 10, of india-rubber, is placed around the

neck 1, so as to fit closely to it, filling the groove 12 between the shoulder 2 and bead 3, 50 as shown in Fig. 5.

In the inside of the cap 7 are found a plurality of helical segments 9 with short intervening spaces 11, through which the projections 4 can pass upon placing the cap in position, so that the lower rounded edge 8 rests on the gasket 10. Upon turning the cap 1 slightly the helical segments 9 engage the projection 4 on the neck 1 and draw the cap downwardly, causing the lower rounded edge 60 8 to impinge upon the gasket 10, which it compresses radially, as well as downwardly, and forces it into intimate contact with lever edge 8 of the cap, the shoulder 2, the neck 1, and bead 3 making an effectual sealing of 65 the jar, as shown in Figs. 1 and 6. But very slight exertion is required to close the jar as thus constructed, and this construction by cooling of the heated contents causes the atmospheric pressure to hold the lid tightly on 70 the jar. By turning the cap in a reverse direction the impingement of the rim 8 on the gasket 10 ceases and air enters the jar, and it is expanded without any difficulty.

By reason of the form of neck and bead 75 and gasket combined with the convex form of the rim 8 the gasket, while effectually closing the vessel, is unimpaired and can be used repeatedly.

Having described my invention, what I 80 claim is—

A closing device for air-tight vessels consisting of a neck having a circumferential bead and shoulder with an intervening groove, a gasket in said groove and a plurality of projecting segments in the neck above said bead in combination with a cap having a plurality of internally-projecting helical segments adapted to engage in the segments on the neck and a convex lower edge adapted to 90 compress said gasket in the groove as set forth.

ALLEN F. WILSON.
